DESCRIPTION

FIG. 1 is a Front Perspective view of a coffee capsule storage display rack showing my new design;

FIG. 2 is a Bottom perspective view thereof;

FIG. 3 is a Front view thereof;

FIG. 4 is a Back view thereof;

FIG. 5 is a Right-side view thereof;

FIG. 6 is a Left-side view thereof;

FIG. 7 is a Top view thereof;

FIG. 8 is a Bottom view thereof; and,

FIG. 9 is a Perspective view of a coffee capsule storage display rack showing in capsule holder.

The broken lines in the drawings depict portions of the coffee capsule storage display rack that form no part of the claimed design.
